UNITED STATES PATENT OFFICE.

RILEY H. OBER AND HOWARD K. OBER, OF FORT JACKSON, NEW YORK.

MAPLE-SUGAR EVAPORATOR.

1,112,380.

Specification of Letters Patent.

Patented Sept. 29, 1914.

Application filed June 28, 1912. Serial No. 706,464.

To all whom it may concern:

Be it known that we, RILEY H. OBER and HOWARD K. OBER, citizens of the United States, residing at Fort Jackson, in the county of St. Lawrence, State of New York, have invented certain new and useful Improvements in Maple-Sugar Evaporators; and we do hereby declare the following to be a full, clear, and exact description of the invention, such as will enable others skilled in the art to which it appertains to make and use the same.

This invention relates to improvements in evaporators, and particularly to maple sugar evaporators.

One object of the invention is to provide a device of this character which will produce the maximum amount of sugar with the minimum expenditure of fuel.

Another object is to provide a device of this character wherein the syrup will be exposed to the heated surface in a thin layer, so that the same will boil faster, and consequently reach the sugaring point in less time than heretofore.

Another object is to provide a device of this character wherein the syrup may be quickly reversed to flow through the pan from either side.

Other objects and advantages will be apparent from the following description and with particular reference to the accompanying drawings.

In the drawings: Figure 1 is a top plan view of the device, Fig. 2 is a side elevation, Fig. 3 is a vertical transverse sectional view on the line 3—3 of Fig. 1, Fig. 4 is a vertical transverse sectional view on the line 4—4 of Fig. 1, only a portion of the furnace being shown, Fig. 5 is a vertical longitudinal sectional view on the line 5—5 of Fig. 1, Fig. 6 is an enlarged vertical sectional view through the syrup regulator, Fig. 7 is a vertical transverse sectional view on the line 7—7 of Fig. 1, Fig. 8 is a vertical longitudinal sectional view on the line 8—8 of Fig. 1, Fig. 9 is a perspective view of the heat deflector, Fig. 10 is a detail sectional view of one of the regulator chambers.

Referring particularly to the drawings, 10 represents the brick-work of a furnace structure, in one end of which are arranged the grate bars 11, and at the same end the smoke stack 12. Disposed on the furnace

structure is the evaporating pan 13, the pan being divided longitudinally by means of the partition 14 in the bottom of which, at one end, is an opening 15. On either side of the partition 14, are the similar partitions 16 and 17, which are provided with the openings 19, at one end and the openings 21 at the opposite end, the latter being controlled by the sliding gates 22 and 23. Extending transversely of the pan between the partition 16 and the adjacent side wall of the pan is a partition 24 having the opening 25, controlled by the sliding gate 26. Similarly formed and arranged on the other side of the pan is a partition 27, having an opening 25' similar to the opening 25 and a gate 29. In the end wall 30 of the pan are formed the openings 31 and 32 having the sliding gates 33 and 34 respectively. By means of these longitudinal and transverse partitions, the pan is divided into the longitudinal compartments *a*, *b*, *c* and *d* and the smaller compartments *e* and *f* respectively at one end of each of the compartments *a* and *d*. In each of the compartments *b* and *c* are formed the longitudinally extending flues 35, one end of each of which discharges into the stack 12 while the other end is in communication with the furnace to receive the heat and products of combustion to permit them to pass therethrough. In the lower end of the stack and below the ends of the flues 35 is a damper plate, which when open permits a direct draft up the stack and when closed forces the heat to travel to the other end of the furnace and through the flues 35 to the stack. From one end of the grate bars to a point adjacent the opposite end of the brick structure extends an inclined deflector 36 to direct the heat into the adjacent ends of the flues. Arranged at one end of the pan, and disposed over the end of the furnace opposite to the grate is a pan 37, which is formed with a series of longitudinally arranged corrugations 38, communication between this pan and the pan 13 being established by means of the openings 31 and 32. Disposed above the flues and connecting with the pan 37 is a U-shaped syrup conducting pipe 39, one end of each of its branches extending into one of the openings 31' and 32' in the end wall 30 so as to discharge the syrup into the pan 37. Formed in the branches of the pipe 39 adjacent the wall 30, are the funnels 40 and 110

41. This pipe 39 serves as a preheater for the syrup so that cold syrup will not be discharged into the pan 37.

Disposed in the compartment *e*, is a regulating device which comprises a tank 43, open at the bottom as indicated at 44 and having the supporting legs 45, to hold the same a suitable distance above the floor of the compartment. Arranged in this tank 10 is a float 46 having a stem 47 extending toward the upper end thereof and connected to a pivoted lever 48, which lever is connected to a valve 49, disposed in a discharge spout 50. This spout is attached to the 15 tank 43 and is adapted to be placed within one or the other of the funnels 40 or 41, a pipe 51 leading from the supply of syrup to the valve. In the drawings the spout is disposed in the funnel 40.

20 In one side wall of the pan 13, within the compartment *a*, is an outlet 52, from which the syrup of the compartment *b* may be drawn off. Formed similarly in the opposite wall of the pan, in the compartment *d* is a 25 draw off opening 53. A stopper 54' is provided to be placed in one or the other of the funnels 40 and 41. In each of the four corners of the pan 13 is a handle 54 by means of which the pan may be readily lifted from 30 the furnace.

In the operation of the device, assuming that the syrup is to be drawn off through the opening 53, the regulator 42 will be placed in the compartment *e* so that the valve spout 50 is disposed in the funnel 40. A stopper 54' is placed in the pipe 39 adjacent the funnel 40 so that the syrup which passes into the pipe 39 will be forced to go clear around through the pipe and enter the 40 pan 37 from the end of the other branch through the opening 32'. The gate 22 and the opening 52 on one side and 29 on the other side are closed, the gate 23 being partially opened to permit some of the syrup to pass into the compartment *f* to prevent the same from becoming dry. The stopper 54' is placed in the funnel 41. The syrup which passes from the pipe 39 through the heating pan 37 will flow over the corrugations, and into the compartment *e* by means of the opening 31, from which it passes by means of the opening 25 into the compartment *a*. The syrup travels to the opposite end of the compartment *a*, enters the compartment *b* through the opening 19 of the partition 16 where it flows over the flues 35, entering the compartment *c* through the opening 15 in the opposite end of the middle wall 14, thence along the compartment *c* 50 through the opening 19 of the wall 17, into the compartment *d* and to the other end of the compartment, where it is drawn off through the opening 53. By means of the float 46, the valve 49 will be opened or closed to regulate the amount of syrup pass-

ing therethrough according to the depth of the syrup in the compartment. The lever 48 is adjustable, so that the valve can be so regulated as to close at various points according as the syrup reaches a depth from 70 two (2) to six (6) inches.

From the foregoing it will readily be seen that because of the flues 35 the syrup will be distributed in a very thin layer, therefore, thus causing the same to boil more 75 quickly, than when the syrup is at a greater depth. This would require that the syrup be heated clear through before the boiling could take place, and as the additional cooler syrup flowed therewith, the boiling process 80 would be greatly retarded. Furthermore, this would require a greater amount of fuel and as a result greatly increase the cost of manufacture of maple sugar and maple syrup. When the syrup becomes too deep in 85 the pan 13, the float will be lifted by the syrup and close the valve 49 until enough syrup has passed from the outlet 53 to permit the float to fall. Thus the syrup is maintained at a constant depth, to permit a more 90 perfect and rapid boiling thereof.

To keep the compartments *e* and *f*, comparatively cool, we place under the inner end of the pan 37 a supporting member 55, having thereon the curved deflector plates 56 95 which direct the heat from the furnace into the flues 35, no heat passing directly into contact with any part of either of the compartments *e* or *f*. By this construction, the regulator may be quickly and easily moved 100 into the opposite compartment when it is desired to reverse the flow of syrup from the pan and draw the same off from the opposite side.

What is claimed is:

1. In a device for evaporating maple syrup, a pan having longitudinal and parallel compartments, heat conducting flues extending longitudinally through the middle compartments, smaller compartments at one 110 end of each of the side compartments, a regulating device disposed in one of the smaller compartments, a syrup conducting pipe disposed over the middle compartment and connected to the regulator, a heating pan at one end of the first-named pan and communicating therewith, the said compartments of the first-named pan communicating with each other, and gates in said communications for regulating the flow of the 115 syrup back and forth longitudinally of the pan through the compartments and out of the opposite side of the pan.

2. In a device for evaporating maple sugar, a syrup pan, a heater pan connected therewith, a plurality of longitudinal parallel compartments in the first-named pan, the outer compartments communicating with the intermediate compartments at one end, the said intermediate compartments 120

communicating with each other at the opposite end, means for regulating the flow of syrup, longitudinal heating flues in the said intermediate compartments, means for conducting syrup to the heater pan, a valve in the syrup conveying means, a float for operating the valve when the syrup has reached a predetermined depth.

3. The combination with an evaporating pan having a U-shaped syrup conducting pipe mounted thereon and provided with a funnel, of a regulator comprising an open-ended vertical tank, a syrup supply pipe leading to and mounted on the tank, a dis-

charge nozzle in the second-named pipe, detachably connected to the funnel, a float in the tank, a valve in the nozzle, and adjustable connections between the float and valve for regulating the flow of syrup to the first-named pipe.

20 In testimony whereof, we affix our signatures, in presence of two witnesses.
